UNITED STATES PATENT OFFICE.

LOUIS McCARTHY, OF BOSTON, MASSACHUSETTS.

STRAIN-INSULATOR.

SPECIFICATION forming part of Letters Patent No. 605,741, dated June 14, 1898.

Application filed January 18, 1898. Serial No. 667,041. (No model.)

To all whom it may concern:

Be it known that I, LOUIS McCARTHY, a citizen of the United States, residing at Boston, in the county of Suffolk and State of Massachusetts, have invented certain new and useful Improvements in Strain - Insulators, of which the following is a specification, reference being had therein to the accompanying drawings.

10 Strain-insulators are frequently employed in the overhead-wire supports for electric railways and for similar purposes. Such insulators are frequently provided with a turnbuckle device, so that not only is one part of 15 the wire or other flexible support insulated from the other portion but the support may also be tightened by the aid of the turnbuckle.

My present invention is an improvement on the strain-insulator shown in Letters Patent 20 granted to me January 10, 1893, No. 489,658. In the device shown in my said patent the sleeve portion of the turnbuckle is in part located within the insulating portion of the device, said sleeve portion forming one of the 25 connections of the insulator. By this arrangement the rotatable member of the turnbuckle is in part within the case of the insulator proper, and this is objectionable, since it is not desirable to have a movable part located 30 within the shell of the insulator proper and in proximity to the insulation. By the construction hereinafter described, which embodies my present invention, I am enabled to obviate these objections.

35 My present invention will be clearly understood from the following description, in which reference is made to the accompanying drawings.

The novel features of my device are pointed 40 out in the claims at the close of this specification.

In the said drawings, Figure 1 is a view of 45 an insulator embodying my invention. Fig. 2 is a similar view, partially in section, to show more clearly the interior construction. Fig. 3 is a similar view, the section being on a plane at right angles to the plane of the section in Fig. 2.

50 Referring to the drawings, A and B are interlocking members, which are embedded in any well-known manner in a globular mass D of insulating material, which is molded around

the interlocking ends of the members A and B under pressure while in a plastic condition and is then allowed to set and harden. The 55 precise construction of this portion of the device is not material to my present invention. Any well-known form of strain-insulator having insulated connections may be employed in place of the connections A B and insulating 60 material D.

The outwardly-projecting end of the connection A is preferably provided with an eye, by means of which it may be secured to a wire or other support. The outwardly-projecting end of the connection B is provided with an enlargement or boss 2, the exterior of which is screw-threaded, as shown at 3. Adjacent the portion 2 is placed the head or enlarged end 5 of the coupling member or sleeve 6. A cylindrical case or sleeve 7, which is 65 interiorly threaded and which is provided with an inwardly-projecting annular flange 8 is then placed on the sleeve 6, the threaded bolt 9 being first removed from the sleeve, and the 70 said case or union 7 is screwed onto the portion 2 of the connection B. The inwardly-turned flange 8 engages the shoulder 10 of the sleeve or coupling member 6 and prevents the 75 head or enlarged end 5 of the said member 80 from being withdrawn from the said case or union 7, while at the same time the said sleeve is free to be rotated. The sleeve or coupling member 6 and the connection B are thus 85 united by a swivel-joint. The outer or free 90 end of the sleeve 6 is interiorly threaded to receive the threaded bolt 9, the latter having at its outer end a head provided with an eye, by means of which attachment may be made to a wire or other support. For the purpose 95 of preventing the case 7 from turning with the member 6 or from becoming otherwise disengaged or displaced I employ a pin 11, which may be plain or threaded and which is inserted in a hole drilled through the sleeve or 100 case 7 and into the head or enlarged portion 2 of the connection B, as will be clear from Figs. 1 and 2. The outer or free end of the coupling member or sleeve 6 is preferably squared, as shown at 12, or otherwise fitted 100 to receive a wrench, by means of which the said sleeve may be turned.

As will be clear, an insulator constructed as above described may be used to tighten or

loosen the support with which it is connected without the slightest danger of affecting the insulation. No movable portion of the device is within the insulation, but is wholly 5 outside the latter, so that no opening or joint is formed in the insulation for any purpose. The danger, therefore, of impairing the insulation, especially when the device is subject to great strain, is reduced to a minimum.

10 What I claim is—

1. An insulator comprising metallic portions separated from each other by interposed insulating material, a case, as 7, secured to the projecting end of one of said connections 15 outside said insulating material, a sleeve secured at one end within said case and provided with a screw-threaded bolt whereby as the sleeve is turned the bolt may be screwed into or out of the sleeve to tighten or loosen 20 the supporting - wire, substantially as described.

2. In an insulator the combination of metallic portions separated from each other by interposed insulating material, the case 7 having the inwardly-projecting flange 8, the 25 sleeve 6 and bolt 9, substantially as described.

3. A strain-insulator comprising metallic portions separated from each other by interposed insulating material, a coupling member connected with a projecting part of one of 30 said metallic portions outside of the insulating material by a swivel-joint, and a connector having an adjustable screw-threaded union with the said coupling member, substantially as described.

In testimony whereof I affix my signature in presence of two witnesses.

LOUIS McCARTHY.
